UNITED STATES PATENT OFFICE.

WILLIAM F. BROWN, OF BROOKLYN, NEW YORK, ASSIGNOR TO THE BIGELOW CARPET COMPANY, OF CLINTON, MASSACHUSETTS.

DESIGN FOR A CARPET.

SPECIFICATION forming part of Design No. 19,840, dated October 8, 1889.

Application filed September 10, 1889. Serial No. 323,560. Term of patent 3½ years.

To all whom it may concern:

Be it known that I, WILLIAM F. BROWN, a subject of the Queen of Great Britain, residing at Brooklyn, Kings county, New York, 5 have invented a new and original Design for Carpets, of which the following is a specification, reference being had to the accompanying photograph, which forms a part of the same.

10 The invention relates to a design to be worked into or upon surfaces, such as carpets or similar fabrics; and it consists in the novel configuration and grouping of figures herein specifically shown and claimed.

15 The accompanying photograph is a face view of a carpet showing my new design.

My design consists of the body A and the border B. The body A is composed of a number of leaf and flower forms and connecting 20 stem-work. An irregular ornamentation forms a background. The border B has an inner margin containing gem-shaped flower forms and other flower and leaf forms. The outer margin is composed of scroll ornaments, and between the margins flower and leaf forms 25 and stem-work are interspersed. An irregular ornamentation forms a background.

What I claim, and desire to secure by Letters Patent, is—

1. A design for carpets, consisting of the body A, substantially as shown.
2. A design for carpets, consisting of the border B, substantially as shown.
3. A design for carpets, consisting of the body A and the border B, substantially as 35 shown.

WILLIAM F. BROWN.
